UNITED STATES PATENT OFFICE.

GEORGE W. PEASE, OF PITTSFIELD, MASSACHUSETTS.

GARMENT.

1,255,334.

Specification of Letters Patent.

Patented Feb. 5, 1918.

Application filed August 24, 1916. Serial No. 116,613.

To all whom it may concern:

Be it known that I, GEORGE W. PEASE, a citizen of the United States, resident of Pittsfield, county of Berkshire, State of Massachusetts, have invented a certain new and useful Garment, of which the following is a specification.

This invention relates to garments such as overalls, pajamas and the like, and has for its objects—

10 First, to produce a union garment having a back drop which may be readily lowered, and which will be properly supported irrespective of the position of the wearer.

15 Second, to exclude dust from the inside of the garment and

Third, to properly support the back drop when the garment is being exhibited for sale.

20 These and further objects will more fully appear from the following specification and accompanying drawings, considered together or separately.

In the drawings,

25 Figure 1 is a rear view of a portion of a garment embodying my invention, showing the back drop raised.

Fig. 2 is a similar view showing a modification.

Fig. 3 is a sectional view on the line 3—3 of Fig. 1.

Fig. 4 is a sectional view on the line 4—4 of Fig. 1.

Fig. 5 is a sectional view on the line 5—5 of Fig. 1 and

35 Fig. 6 is a sectional view on the line 6—6 of Fig. 1.

In all views like parts are designated by the same reference characters.

40 My invention relates to a garment of the type disclosed in my copending application for patent filed on or about the 13th day of June 1916, Serial No. 103,371.

45 My improved garment comprises the coat or upper part 1, which is in the form of a jacket or jumper. To this is permanently attached the lower part 2, in the form of trousers or pants. The line of connection is about at the waist line 3.

50 The lower part 2 is provided with a suitable back drop 4, having an extension 5, extending up inside the lower edge of the back of the coat 1. The back drop extension 5 is supported inside of the lower part of the coat 1 by suitable fastening means. These 55 fastening means are removed from the corners of the back drop extension. The fasten-

ing means, indicated at 6, may be in the form of buttons. These buttons engage suitable button holes in a flap 7 sewn or otherwise secured to the inner part of the coat 1. 60 This flap may be readily reached for buttoning or unbuttoning the extension. The upper part of the back drop 4 is supported in position by suitable fastenings 8, preferably in the form of buttons engaging suitable 65 button holes in the coat 1. The middle part of the back drop is preferably supported by fastenings 9, preferably in the form of buttons engaging suitable button holes in the side of the trousers 2. 70

A suitable dust excluding flap 10 is sewn or otherwise secured to the inside of the coat 1 above the upper edge of the back drop extension 5. The corners of this flap are suitably secured in position by means of fastenings 17 in the form of buttons or other devices, engaging suitable button holes formed in the coat 1. The back drop 4 is provided with the usual back pockets 11, and the sides of the trousers 2 are provided with 80 usual side pockets 12, but it is to be understood that the details of the pockets form no part of the invention.

For the purpose of allowing the wearer perfect freedom of movement so that he may 85 bend over and straighten up without the garment opening in the back and exposing his clothing, I provide the following instrumentalities:

The coat 1 is provided with a suitable stay 90 or reinforced band 14. This stay is sufficiently stiff so that when the wearer bends over and straightens up the back of the coat will be held down. This stay may be made in any suitable manner, a typical one being 95 shown in Fig. 6. In the embodiment chosen for illustration the stay is formed of four layers of the material stitched inside of the center seam. It should be understood, however, that this stay may be made in any other 100 suitable way.

The back drop extension is also provided with a suitable stay or band 15, which preferably extends from the waist line 3, up to the line of the buttons 6. This stay may be 105 made in any suitable manner, for example as shown in Fig. 6. It will support the back drop extension so that when the wearer bends over and straightens up this back drop extension will not fall down and expose his 110 clothing.

The dust excluding flap 10 is also provided

with a similar stay 16. The purpose of this stay is to keep the dust excluding flap in position so that it will not roll up when the wearer bends down and straightens up. It is to be understood that the garment is cut sufficiently full so that when the wearer bends down or forward the fastenings will not be broken.

The corner fastenings 13 for the back drop extension are not essential and may be omitted as shown in Fig. 2. In this embodiment of the invention the back drop extension is supported solely by the fastenings 6.

When my device is exhibited for sale and is held up before the prospective customer, the back drop extension is suitably supported in the center and does not produce an opening or gap as is the case where there are no such supports. At the same time the back drop may be readily lowered and raised, the button holes in the flap 7 being readily reached.

In accordance with the provisions of the patent statutes I have described the principle of my invention, together with the apparatus which I now consider to represent the best embodiment thereof, but I desire to have it understood that the apparatus shown is merely illustrative, and that the invention may be carried out in other ways.

Having thus described my invention what I now claim as new and desire to secure by Letters Patent, is:

1. A union garment comprising a coat and trousers permanently united at some place in the front, the back of the coat portion terminating at approximately the waist line, a back drop, said back drop extending up inside of the back of the coat to a considerable distance above the waist line, means for securing the back drop to the sides of the coat at approximately the waist line, and additional fastenings inside of the coat and located at a distance from the sides thereof and connecting the top of the back drop to the coat at a considerable distance above the first mentioned fastenings.

2. A union garment comprising a coat and trousers permanently united at some place in the front, the back of the coat portion terminating at approximately the waist line, a back drop, said back drop extending up inside of the back of the coat to a considerable distance above the waist line, means for fastening the back drop to the sides of the coat at approximately the waist line, a flap inside of the coat wholly above the fastening means and additional means above the first mentioned means for fastening the upper edge of the back drop to the flap at a point removed from the sides of the coat portion.

3. A union garment comprising a coat and trousers permanently united at some place in the front, the back of the coat portion terminating at approximately the waist line,

a back drop, said back drop extending up inside of the back of the coat above the waist line, a flap containing button holes attached to the inside of the back of the coat above the waist line, buttons carried by the back drop engaging said button holes, and a dust excluding flap secured to the inside of the back of the coat, and also inside of the button hole flap and extending down inside of the back drop.

4. A union garment comprising a coat and trousers permanently united at some place in the front, a back drop, said back drop extending up inside of the back of the coat above the waist line, fastenings carried by the back drop extension and removed from the corners thereof, a flap carrying co-operative button holes secured to the inside of the coat and engaging the aforesaid fastenings and a stiffening stay on the back drop extending up to the line of the fastenings.

5. A union garment comprising a coat and trousers permanently united at some place in the front, a back drop, said back drop extending up inside of the back of the coat above the waist line, buttons carried by the upper part of the back drop and removed from the corners thereof, a flap carrying button holes secured to the inside of the back of the coat, said button holes engaging with said buttons, a dust excluding flap attached to the inside of the back of the coat and extending inside of the back drop, fastenings for the corners of the dust excluding flap, a stiffening stay on the middle of the back drop, a stiffening stay on the middle of the back part of the coat and a stiffening stay on the middle of the dust excluding flap.

6. A union garment comprising a coat and trousers permanently united at some place in the front, a back drop, said back drop extending up inside of the back of the coat above the waist line, and a stiffening stay carried by said back drop.

7. A union garment comprising a coat and trousers permanently united at some place in the front, a back drop, said back drop extending up inside of the back of the coat above the waist line, a dust excluding flap secured to the inside of the back of the coat and lying inside of the back drop, and a stiffening stay associated with said dust excluding flap.

8. A union garment comprising a coat and trousers permanently united at some place in the front, a back drop, said back drop extending up inside of the back of the coat above the waist line, buttons carried by the upper part of the back drop and removed from the corners thereof, a flap carrying button holes secured to the inside of the back of the coat, said button holes engaging with said buttons, a dust excluding flap attached to the inside of the back of the coat and extending inside of the back drop, fastenings

for the corners of the dust excluding flap, a stiffening stay on the middle of the back drop, and a stiffening stay on the middle of the back part of the coat.

- 5 9. A union garment comprising a coat and trousers permanently united at some place in the front, the back of the coat portion terminating at approximately the waist line, a back drop, said back drop extending up into
10 side of the back of the coat to a considerable distance above the waist line, means for securing the back drop to the sides of the coat at approximately the waist line, fastening means inside of the coat and connecting the
15 upper edge of the back drop to the coat at

the sides of the latter and at a considerable distance above the first mentioned fastening means, additional fastening means for securing the upper edge of the back drop to the coat at a considerable distance above the 20 waist line, said latter fastening means being located at a distance from the sides of the coat.

This specification signed and witnessed this 22nd day of August, 1916.

GEORGE W. PEASE.
